UNITED STATES PATENT OFFICE.

STEPHEN NEWCOMBE WELLINGTON, OF LONDON, ENGLAND, ASSIGNOR TO COALITE
LIMITED, OF LONDON, ENGLAND.

APPARATUS FOR DISCHARGING AND QUENCHING COKE.

1,274,826.

Specification of Letters Patent.

Patented Aug. 6, 1918.

Application filed April 17, 1916. Serial No. 91,791.

To all whom it may concern:

Be it known that I, STEPHEN NEWCOMBE WELLINGTON, a subject of the King of Great Britain and Ireland, residing at 39 Mincing

5 Lane, London, E. C., England, have invented certain new and useful Improvements Relating to Apparatus for Discharging and Quenching Coke, of which the following is a specification.

10 This invention relates to apparatus for discharging and quenching high or low temperature coke or the like from vertical retorts, and is more especially applicable for the discharge of the residue of distillation at

15 comparatively low temperatures. The invention has for its object to effect the discharge of the coke from vertical retorts so as to avoid waste, to improve the coke, and also to effect the quenching of the coke in

20 a simple and effective manner without contact of the coke with the water used, and generally to provide an apparatus simple in construction and effective in operation.

According to the invention I provide re-

25 ceptacles for the reception of the whole charge from the retorts, and I mount the receptacles upon a carriage to run on rails mounted immediately beneath the retort setting, so that thus the receptacles mounted

30 upon the carriage can be brought beneath the respective retorts of the battery or setting in succession. I provide gear for the purpose of lowering the charge into the receptacles, the gear being mounted advan-

35 tageously upon a separate carriage and mounted to run beneath the carriage upon which the receptacles are mounted. According to the invention also the gear com-

40 prises one or more rams adapted from be-

neath to pass through the receptacle or re-

45 ceptacles to take the weight of the bottom cover plate or door and to lower the bottom cover plate or door with the charge into the receptacle; the gear advantageously com-

50 prises an electro-motor and controller with a clutch conveniently provided, by which the motor may be employed for driving the carriage upon which the gear is mounted to

55 run on rails, or in the alternative for lifting

or lowering the rams, while the gear also

56 comprises means manually operated by

which fine adjustment of the position of the

ram or rams and carriage may be effected, or if necessary also of the carriage upon which the receptacles are mounted.

60 The invention comprises the constructional features which are hereinafter described in an apparatus provided according to the invention.

In the accompanying drawings is illustrated, by way of example, an apparatus according to the invention.

Figure 1 is a side elevation partly in section of a modified construction of the apparatus.

65 Fig. 2 is an end elevation of the apparatus shown in Fig. 1.

Fig. 3 is a plan view of the gearing operating the rams to an enlarged scale.

70 Fig. 4 is a sectional elevation of the gearing corresponding to Fig. 3 taken on line of spindle j.

Fig. 5 is a front elevation of the gearing illustrated in Figs. 3 and 4.

75 In carrying the invention into effect as illustrated in Figs. 1 and 2 in the construction of a quenching machine provided according to the invention, I provide two receptacles d mounted upon a carriage frame e in such position that two alternate vertical 80 retorts of a battery may be discharged simultaneously and I provide each receptacle with a sliding cover plate 1 provided on each side and beneath the plate with toothed racks adapted to mesh with pinions 2 mounted each upon a spindle 3 carried immediately beneath or at the side of the outwardly flaring upper end of each receptacle. A chain wheel and chain 4 (Fig. 2) serve to cause the rotation of the spindle 3 and to 85 cause the cover plate 1 to slide to or fro for closing or opening the top of each receptacle.

Upon the carriage frame e a tank 5 is 90 mounted adapted to contain the water for quenching the coke in the respective receptacles. The lower ends of the receptacles pass into the tank so that at their lower ends the receptacles are completely surrounded by the water contained in the tank. Holes 6 are formed in the top of the tank 5 95 in a position corresponding to the respective receptacles and of a larger diameter than that of the receptacles so that thus off the water being sprayed from the upper end

of the receptacles on to the outer surface thereof the water returns to the tank.

I mount a pump and motor equipment in a position above the tank as illustrated in Figs. 1 and 2 with the suction pipe 7 extending to near the bottom of the tank and with its upper end connected to the pump 8 which is operated by the motor 9'. The pump outlet discharges into the water pipe 9 by which water is supplied to the spray pipes 10 which completely surround the respective receptacles, the spray pipes 10 being provided with orifices throughout their length by which water is directed inwardly toward the outer surface of the receptacle. A platform 11 serves for access by the attendant to the upper part of the receptacles.

A central overflow outlet pipe 9² may be provided in the tank in the position indicated in Fig. 1 and partitions 12' may extend into the tank short of the bottom as a means for preventing the water being spilled on a too sudden movement of the quenching machine or on a too sudden arrestment of this movement.

The motor equipment and gear for causing the movement of the quenching machine upon the rails upon which it is mounted is advantageously provided in the front part of the carriage frame as illustrated in Fig. 1, the motor being indicated by 13, the controller by 13', and the gear by 14 by means of which movement is imparted to the axle 15. A contact arm 16 is provided in position beneath the carriage frame *c* by means of which current may be passed to the motor from conductors 17 of a three phase circuit mounted near the side wall of the well in which the discharging machine is mounted as illustrated in Fig. 2.

Each of the receptacles at its base and on each side is provided with a sliding plate 18 and these sliding plates are provided with toothed racks engaging with segments 19. One of the segments is mounted upon a spindle 20 transversely disposed across the carriage frame while an operating lever 21 is mounted upon the outwardly protruding extremity of the spindle 20 and this operating lever 21 is extended at one side for the purpose of connection with the corresponding toothed segment 19 by means of a link 22, while at the other side of the spindle 20 opposite to that upon which the operating lever 21 is mounted a short downwardly extending arm is provided corresponding to the downwardly extending part of the lever 21 for connection with a second link 22 mounted upon the other side of the carriage frame. A link 23 is provided on each side to connect the respective sets of segments together of each of the receptacles so that the respective sliding plates 18 of each receptacle may be operated by the single operating hand lever

21. The normal position of the sliding plates 18 is indicated in Fig. 1 and these protrude within the receptacle and form ledges on each side for carrying the bottom door 24 upon which the charge is supported.

The inwardly protruding edges of the sliding plates 18 are formed with curved downwardly flaring flanges 25 which serve to bring the ram 26 on its upward movement into precise coincidence with the center of the receptacle.

It will thus be understood that the bottom doors of the retorts to be discharged are retained with the charge in the receptacles. For this purpose the carriage frame *c* is extended at one end in order that two spare doors 24 may be transversely mounted in position thereon corresponding to the position of the retorts, and these after the discharge of the retorts may immediately be lifted into position to close them so that they may be immediately re-charged.

Gripping arms 27 may be mounted beneath the carriage frame *c* to prevent liability of the carriage frame being upset on the spare bottom doors 24 being lifted off the frame. These gripping arms 27 engage the slides of the respective rails upon which the carriage frame *c* is mounted to run in such manner that they do not normally contact with the rails but permit of freedom of movement.

In carrying the invention into effect in the construction of the discharging machine as illustrated, I provide a base-plate 28 upon the carriage frame *f* with bosses 29 suitably provided for the reception of ball bearings, upon which worm wheels may rotate, the worm wheels being provided with an internal thread corresponding to the external thread provided upon the ram spindles *g*. I provide a longitudinal shaft *h* with worms in determined position for engagement with the worm wheels referred to, so that thus the threaded spindles *g* of the rams may be moved upwardly or downwardly on the rotation of the longitudinal shaft *h* in one direction or the other. The worm wheel may be suitably incased, as may also the worm. For the purpose of preventing the rotation of the respective threaded ram spindles *g* I mount on each of their lower extremities an arm 30 which is provided with lateral lugs 31 at the end to engage the respective lateral edges of the corresponding arm near its boss 32 by which it is mounted at the end of the threaded spindle. Any other means for the same purpose, may, however, be provided.

The motor 33 is advantageously mounted in direct line with the longitudinal shaft *h*, and one end of the motor spindle *j* is disposed close to the end of the longitudinal

shaft *h*, and the respective members 34, 35 of a clutch are mounted on the adjacent ends of the motor spindle and longitudinal shaft, so that thus the longitudinal shaft *h* 5 may be caused to rotate with the motor spindle *j* or be disconnected therefrom according to the position of the movable member 35 of the clutch.

Upon the end of the longitudinal shaft *h* 10 adjacent, or upon the boss of the clutch member 34 carried thereby, a toothed pinion 36 is mounted to engage with a corresponding toothed wheel not shown mounted upon a spindle 38 through which movement is 15 imparted to a circuit breaker 39 disposed in an adjacent position so that on the rotation of the longitudinal shaft *h* on the operation of the motor 33 in one direction or the other, that is to say, in the direction necessary for 20 the upward or downward movement of the ram 26, excessive movement of the ram may be prevented. The sign 40 indicates a brake of any usual construction, preferably a magnetic brake, whereby movement of the spindle of the motor may be checked or stopped. A magnetic brake 40 may also be provided to arrest the movement of the motor 33 25 and motor spindle.

Adjacent the clutch 34, 35 and immediately beneath the extremity of the motor spindle *j* gear is provided by which movement may be imparted to a second longitudinal shaft *l* through which the rail wheels are rotated for the movement of the carriage frame *f* from place to place. This gear may consist of two toothed wheels 41, 42, the larger 41 of which may be disposed so as to be engaged by the toothed pinion 35 integrally provided on the movable member 35 of the clutch, while the second toothed wheel 42 may be integrally provided with the toothed wheel 41, and this second toothed wheel 42 may engage with a toothed wheel 43 mounted at the extremity of the second longitudinal shaft *l*. The second longitudinal shaft *l* is advantageously mounted beneath the carriage frame *f* and is adapted to cause the movement of one of the axles 44 by which the carriage frame *f* is supported. For this purpose a worm may be mounted upon the extremity of the second longitudinal shaft *l* to engage with the corresponding worm wheel mounted upon the axle 44.

55 The respective adjacent ends of the shaft *h* and spindle *j* are carried within suitable bearings upon a support 53 over which a cover 54 is applied and bolted.

I provide the hand lever 46 for operating 60 the clutch 34, 35 upon a spindle 48 disposed in a convenient position accessible to the attendant who may stand upon a platform 49, disposed lower than the level of the top of the carriage frame *f* & corresponding hole

or recess being formed in the top of the 65 carriage frame and immediately above the platform 49 while the platform is conveniently supported from the frame as illustrated in Fig. 2.

I mount upon the spindle 48 carrying the 70 clutch operating lever 46, a second hollow spindle 50 upon which at one end I mount a hand lever 47 in a position adjacent to the operating hand lever 46 of the clutch 34, 35, this second lever 47 being intended for the 75 operation of the clutch 51 by means of which the mechanism is rendered operable by the hand wheel 52. For this purpose a gear wheel 55 is mounted upon the end of the motor spindle *j* in a position adjacent to the 80 clutch 34, 35 before referred to, and this gear wheel 55 engages with a corresponding pinion mounted upon a spindle 57 disposed parallel with the motor spindle *j*. The spindle 57 is at one end carried upon the 85 support 53 and at the other upon the supporting frame 58. This latter serves also to support the motor spindle and to receive one side of the casing or guard 59, which at the other side is mounted upon the support 53. At the end of the spindle 57 the hand wheel 52 is mounted in a position accessible to the attendant so that on the clutch 51 intended for permitting operation by hand being caused to engage, the brake magnet 90 is lifted to permit of easy operation of the gear by hand. By such means it will be understood that the hand operated mechanism is available for adjusting the position of the carriage frame *f* in relation to the 100 receptacles *d* mounted on the quenching machine as well as the position of the rams 26.

A contact lever 60 may be provided to extend above the level of the carriage frame and pivotally mounted in position thereon in 105 such manner that it may be displaced on the contact lever 16 of the quenching machine being moved in position over it. For this purpose an arm on the contact lever extends below its pivoting point and is engaged on 110 each side by means of spiral springs which tend to maintain it in its upright central position. The contact arm 60 is advantageously provided with three contacts where, as is preferred, a three phase electric circuit is 115 used.

It will be understood that the quenching machine is adapted to run upon rails over a pit within which the discharging mechanism is adapted to run upon rails of a narrower gage than that upon which the quenching machine runs, the pit being provided centrally sufficiently deep to permit of the complete retraction of the ram spindles. Such an arrangement of the quenching and 120 discharging machines is indicated in Figs. 1 and 2.

The operation may be readily understood.

from the foregoing. I bring one of the carriage frames, preferably frame *e*, into position over the pit, either before or after I have cooled or quenched the coke in the receptacles. I then bring the lower frame *f* into position and cause the rams to rise and thus push the coke out at the top.

The receptacles may be discharged in any convenient manner. I prefer to discharge them by lifting the coke after it has been cooled so that it may be deflected on to a conveyer and then passed away for loading into trucks or barges, the coke being thus broken into large pieces and without considerable waste.

It will thus be seen that on the two carriage frames movable with respect to each other, I have embodied all the parts necessary for effecting rapid and safe discharge of coke. The lower frame *f* may serve the upper frame *e* or several of them, in any position and at any time desired. One upper frame may serve several ovens.

It will be noted that in the operation of my device, the machine as a whole is brought to approximate position with respect to the ovens by means of motor 33. By means of motor 13, the carriage frame *e* is brought to position with respect to alternate retorts of a coke oven battery. These retorts are discharged into receptacles *d* which are closed. The hot coke is cooled therein by spray pipes, 10. After cooling it is discharged preferably at the upper end upon a conveyer. Meantime the machine may have been permitted to receive and cool coke from other retorts of the battery.

I claim:—

1. In coke treating apparatus, in combination, a track, a carriage, receptacles mounted on said carriage, a second carriage and track below the first, coke discharging devices mounted upon the second carriage, and means for bringing the receptacles and discharging means into registry, whereby said receptacles may be discharged.

2. In coke treating apparatus, in combination, a track, a carriage mounted to move on said track, receptacles for containing coke on said carriage, a tank, the lower ends of said receptacles extending into said tank, a spraying means for each receptacle, and means whereby water may be raised from said tank, sprayed around said receptacles and allowed to run back into said tank.

3. In coke treating apparatus, in combination, a track, a carriage mounted to move on said track, a motor on said carriage, said motor adapted to be connected to drive the wheels thereof, a tank on said carriage, coke receptacles on said carriage, the lower ends of which extend through the tank, a spraying device, a pump, and a motor on said tank, said spraying device being adapted to

cover said receptacles and coke and permit the cooling water to drain back into the tank, and means for removing coke from said receptacles.

4. In combination a carriage, a receptacle, for coke, a tank through which the lower end of the receptacle extends, a bottom for said receptacle, a second carriage, coke ejecting rams on said second carriage, a motor on said second carriage for driving it, and connections whereby said motor may be used to lift the ejecting rams.

5. In a coke discharging and quenching apparatus, in combination, a carriage, coke holding receptacles thereon, a tank through which said receptacles extend, a pump, and connections whereby water may be pumped against the outside of said receptacles to quench the coke therein, closures for the top of said receptacles, bottoms slideable through said receptacles, supports for said bottoms, means for removing said supports, and means for raising said bottoms from beneath to discharge quenched coke and to lower said bottoms through said receptacles.

6. In a coke quenching and discharging apparatus, in combination, a receptacle for the coke, a bottom fitting in said receptacle and adapted to be raised and lowered therethrough, a carriage on which said receptacle is mounted, a tank through which the lower end of said receptacle passes, means for raising said bottom and ejecting said coke thereon, and a second bottom adapted to be raised into position immediately after the discharge of a coke retort to close it, and to be lowered through the receptacle to charge the latter with coke.

7. In a coke quenching and discharging device, in combination, a frame, a coke receptacle thereon, the sides of said receptacle being vertical, a door closure for said receptacle, means for holding and supporting said door, means for lifting said door or closure from bottom to top through said receptacle to discharge it of coke, a carriage for carrying said last-named means, a motor for moving said carriage, and connections whereby said motor may be connected to said lifting means.

8. In a coke quenching apparatus, in combination, means for receiving a charge of coke, means for pumping a supply of cooling water against the sides of said receiving means, a carriage on which said receiving and pumping means are mounted, a second carriage, and on said second carriage, discharge effecting means.

9. In a coke quenching apparatus, in combination, a carriage, a coke receptacle, a water tank and a spraying device mounted on said carriage, a second carriage, a pit wherein said carriage may be moved below said first carriage, and an ejecting device on

said second carriage, said device adapted, when the carriages are in position, to register with the bottom of said coke receptacle to discharge coke therefrom.

- 5 10. In a coke quenching apparatus, in combination, a carriage, a receptacle having vertical sides on said carriage, a closure for the bottom of said receptacle, a flange for supporting said closure, means for removing 10 said supporting flange, and a plunger for supporting said closure and moving it up and down through said receptacle after the closure supporting flange has been removed.
11. In an apparatus for discharging and 15 quenching coke, a carriage, receptacles for coke upon said carriage, a second carriage, discharging mechanism upon said second

carriage, a motor on said second carriage, means for connecting said motor to said discharging means, and auxiliary or alternate 20 hand means for actuating the carriage.

12. In coke quenching apparatus, in combination, coke receptacles, a tank and a pump on said carriage for quenching coke by applying water to the exterior of said receptacle, a second carriage, a discharging device on said second carriage, and means whereby 25 said device may be moved into proper registry to discharge the said receptacle.
